UNITED STATES PATENT OFFICE.

ALONZO LINTON BAUSMAN, OF SPRINGFIELD, MASSACHUSETTS, ASSIGNOR TO NATIONAL EQUIPMENT COMPANY, OF SPRINGFIELD, MASSACHUSETTS, A CORPORATION OF MASSACHUSETTS.

DEPOSITOR

Application filed October 19, 1923. Serial No. 669,543.

To all whom it may concern:

Be it known that I, ALONZO LINTON BAUSMAN, a citizen of the United States, residing at Springfield, in the county of Hampden and State of Massachusetts, have invented 5 new and useful Improvements in Depositors, of which the following is a specification.

This invention relates to improvements in 10 depositors and particularly to depositors which are adapted to deposit a plurality of kinds of different confectionery materials.

Depositors for simultaneously discharging 15 two or more kinds of confectionery have been provided heretofore, as I am aware, but such depositors generally discharge the two or more substances from one nozzle or from multiple nozzles which are concentrically located. These depositors, while suitable for forming ornamental deposits 20 on biscuits and the like are not suitable where an intermingling of the various kinds of confection is not desired. The present invention is concerned with improvements in depositors whereby deposits of two or 25 more kinds of confection may be simultaneously made in one mold, in such a manner that the various kinds of confection are not substantially intermingled.

The invention has for an object the provision 30 of means whereby an ordinary depositor can readily be converted into one adapted for the special use described and contemplates the provision of a special pump bar which may be substituted for the pump 35 bar of the ordinary depositor together with a partitioning device which can be applied to the supply receptacle of the ordinary depositor to divide it into a plurality of compartments.

According to this feature, the manufacturer 40 can standardize his depositor line and, by a simple substitution of a special pump bar and a partitioning device, can convert the standard depositor into one 45 adapted for the special use described.

According to another feature of the invention, the pump cylinders are arranged all 50 in one transverse row and in alignment and each of the plurality of supply receptacles is connected to a nozzle in this transverse row so that different materials may be discharged through different nozzles in such row.

Frequently, only two kinds of material

are desired and in such case one receptacle 55 is connected to alternate nozzles of the transverse rows and the other receptacle is connected to the remaining nozzles of the row.

According to another feature of the invention 60 a removable partitioning device, consisting essentially of a flexible plate of thin metal, is provided which can be slipped in place in the supply receptacle and held in place by clamping devices applied at one 65 end only, such devices acting to hold the plate in bowed form in contiguous relation with abutments provided for the sides and other end of the plate.

Other objects and advantages will appear 70 in the following description and in the illustrative embodiment of the invention in the accompanying drawings, in which:—

Fig. 1 is a side elevational view of a depositor embodying the invention; 75

Fig. 2 is a fragmentary cross sectional view thereof taken on the line 2—2 of Fig. 1;

Fig. 3 is an enlarged fragmentary sectional elevational view showing the improved pump bar and the receptacle partitioning device; 80

Fig. 4 is a fragmentary sectional elevational view taken similarly to Fig. 3 but in a different plane; 85

Fig. 5 is a rear elevational view of the pump bar;

Fig. 6 is a fragmentary sectional plan view taken on the line 6—6 of Fig. 3; 90

Fig. 7 is a fragmentary plan view of the cut off bar; and

Fig. 8 is a fragmentary sectional view taken similarly to Fig. 3 and showing a different positioning of parts.

Referring to these drawings, the depositor, for the most part, is of the usual well known construction. It includes spaced side frames A which support a supply receptacle b and mechanism for moving trays, such as t, usually in a step by step manner, beneath the receptacle b. The tray moving mechanism includes two laterally spaced conveyer chains c supported from shafts d and e and driven from the former by ratchet and pawl mechanism, indicated conventionally at f. The trays ride on runways g, which also receive and support chains c in their working stretch of travel, and are 100 105

held in line by side guides *h*. The chains *c* carry lugs *i* which engage and move the trays. The depositor as thus far described, is generally similar to that disclosed in my U. S. Letters Patent No. 1,169,602, granted January 25, 1916, to which reference may be made for a more complete disclosure.

The depositor also includes a pump bar 10 which is suitably fixed, as indicated, to the front face of receptacle *b* and is provided with a plurality of pump cylinders 11, all of which are aligned in one transverse row. Slidably mounted in each cylinder 11 is a piston 12 which emerges from the upper end of its cylinder through a stuffing box 13 and is provided with a T-head 14. The heads 14 of all the pistons are received in a corresponding groove in a cross bar 15 which is slidably mounted near its ends in guide members 16 fixed to the front face of the receptacle *b*. The bar 15 is provided at its ends with trunnions 17, which are connected by links 18 to suitable driving mechanism, such as that illustrated and described in the patent above identified.

Fixed to the lower face of the pump bar 10 is a bottom closure member 20 which is recessed longitudinally in its upper face to slidably receive a cut off bar 21, shown in detail in Fig. 7. In the members 20, and depending downwardly therefrom, are mounted a plurality of discharge nozzles 22, one located beneath each cylinder 11. In the pump bar 10 and located behind the cylinders 11 are a transverse row of supply ports 23, one for each cylinder, which ports are vertically disposed in parallel relation with their cylinders. The cut off bar 21 is provided with a plurality of elongated holes 24 therethrough, one for each cylinder, and, intermediate these holes, are a plurality of holes 25, one for each cylinder. The holes 24 are adapted to connect the ports 23 to their respective cylinders in a manner clearly obvious from Fig. 3 and the bar 21 is movable laterally to carry the holes 24 out of communication with ports 23 and cylinders 11 and into the position shown in Fig. 6. In such position, which is also illustrated in Fig. 8, the holes 25 in bar 21 serve to connect the nozzles 22 to their respective cylinders 11. The position of bar 21 first above described is that which obtains during the suction stroke of pistons 12 and the second position is that which obtains during the discharge stroke of the pistons. The construction and mounting of the cut off bar is similar to that ordinarily used and it is actuated in the usual manner, as by the mechanism disclosed in the prior patent above identified.

The member 20 is provided with a dovetail 26 adjacent its lower rear edge which is received in a corresponding groove in the front face of receptacle *b*. The member 10,

connected to member 20, is likewise provided with a dovetail 27 and a gib 28, secured to the front face of receptacle *b*, serves to hold the rear faces of the connected members 10 and 20 tightly against and in contiguous relation with the front face of receptacle *b*.

The latter is of usual form, having an open upper end, which, however, is usually closed when the depositor is in operation, and a heating jacket 29. The receptacle is provided with the usual discharge passage 30 in the front face thereof near its lower end. For partitioning the receptacle *b* and thereby forming compartments 31 and 32 for different confectionery materials, I provide a flexible plate 33 which may advantageously be made of thin sheet metal. To this plate 33 an angle iron 34 is riveted along its upper edge, which serves to stiffen the plate against transverse bending and for another purpose later to appear. Secured within and to each side wall of the receptacle are angle iron abutments 35, each of which extends, from a substantially central location near the upper end of the receptacle, downwardly in an arc of a circle, and terminates in discharge passage 30, substantially centrally between the upper and lower walls thereof. Above the lower end of angle irons 35 and spaced therefrom, by a distance commensurate with the thickness of plate 33, are short angle irons 36, which are located almost entirely in discharge passage 30 and are secured one to each side wall thereof. The angle irons 36 are preferably bevelled, as at 37, for the purpose of guiding the lower end of plate 33 into the groove between the angle irons 35 and 36, during the operation of inserting the plate 33 in the receptacle. The angle irons 36 serve as guides to direct the lower edge of plate 33, during the same operation, into a transverse groove 38 which is formed in the rear face of pump bar 10. This groove is preferably formed with diverging walls, as shown, to assist in guiding the plate 33 to a proper seat in the bottom of the groove, such bottom forming an abutment against which the lower edge of plate 33 is tightly pressed, as will appear. To further assist in guiding plate 33 into groove 38 a single short angle iron 39 is riveted to the under side of plate 33 near its lower end and this angle iron slides on the bottom wall of passage 30 and prevents the plate 33 from bending intermediate its ends to such a degree as to prevent its insertion into groove 38. Secured to the top of the receptacle *b* and projecting inwardly in overlying relation with the angle iron 34 are lugs 40, one on each side of the receptacle, and threaded into each lug is a thumb screw 41 which can be turned down to apply pressure on the upper edge of plate 33 and thereby force it

tightly against the side abutments 35, thereby forming a tight partition wall between the compartments 31 and 32. The lower end of plate 33 is inserted between guides 36 and angle irons 35 and then pushed downwardly, being guided as described into groove 38. The plate is then bowed inwardly until the angle iron 34 can be caught under the ends of screws 41, which are then turned down to apply the final holding pressure.

Referring now to the pump bar 10, there are provided in its rear face, upper and lower supply slots 42 and 43 which are longitudinally disposed in parallel relation and which communicate with passage 30 above and below plate 33, respectively. The slot 42 is connected to every other supply port 23 by vertical passages 44 and the slot 43 is connected to the other supply ports by passages 45. Thus, adjacent pump cylinders are supplied from different compartments and adjacent nozzles 22 may emit different confectionery materials.

In use, the trays *t* (Fig. 2) are filled with starch and rows of molds *m* are formed therein which are considerably longer than the ordinary mold, such as is used for the centers of chocolate creams. The molds *m* are much the same in size and shape as the so-called "lady fingers" and are so located that as a row of molds comes to rest beneath the row of nozzles 22 each mold will underlie two adjacent nozzles, whereby two kinds of confection will be deposited simultaneously in different locations in the same mold. The confections are thus deposited side by side in the same mold and do not intermingle to any substantial extent although, of course, the line of division between the two kinds of confection may be somewhat irregular.

The invention has been disclosed herein, in an embodiment at present preferred, for illustrative purposes, but the scope of the invention is defined by the appended claims rather than by the foregoing description.

What I claim is:

1. The combination in a depositor with the receptacle for the material to be deposited, of a flexible partition wall therefor, an abutment provided in connection with the receptacle to receive the lower end of said wall, abutments on the sides of said re-

ceptacle against which the side edges of said wall are adapted to engage, and means for applying pressure to the upper edge of said wall to cause it to engage said abutments.

2. The combination in a depositor with the receptacle for the material to be deposited, of a flexible partition wall therefor, an abutment provided in connection with the receptacle to receive the lower end of said wall, curved abutments on the sides of said receptacle against which the side edges of said wall are adapted to engage, and means for applying pressure to the upper edge of said wall and causing it to bow inwardly against said curved abutments.

3. The combination in a depositor with the receptacle for material to be deposited, said receptacle provided with an open upper end and a discharge passage in its front wall, an angle iron abutment on each side wall extending in an arc of a circle from a position adjacent said upper end to a position adjacent said passage and intermediate the upper and lower walls thereof, a thin metal partition plate extending transversely across the receptacle, an abutment adjacent said passage to receive the lower end of said plate, and means on the receptacle for applying pressure to the upper edge of said plate and bending it against said angle iron abutments.

4. The combination in a depositor with the receptacle for material to be deposited, said receptacle provided with an open upper end and a discharge passage in its front wall, an angle iron abutment on each side wall extending in an arc of a circle from a position adjacent said upper end to a position adjacent said passage and intermediate the upper and lower walls thereof, a thin metal partition plate extending transversely across the receptacle, an abutment adjacent said passage to receive the lower end of said plate, and an abutment near said upper end of the receptacle for the upper end of the plate, said plate adapted to be engaged with its lower abutment, flexed to engage said curved abutments and held in flexed position by the upper abutment.

In testimony whereof I have affixed my signature.

ALONZO LINTON BAUSMAN.
